UNITED STATES PATENT OFFICE.

HENRY H. CRANE, OF FLORAL PARK, NEW YORK, ASSIGNOR TO HUBER MFG. CO., OF NEW YORK, N. Y., A CORPORATION OF NEW YORK.

LOCK.

1,273,036.

Specification of Letters Patent. Patented July 16, 1918.

Application filed March 28, 1918. Serial No. 225,202.

To all whom it may concern:

Be it known that I, HENRY H. CRANE, a citizen of the United States, whose residence and post-office address is Floral Park, Long Island, in the State of New York, have invented certain new and useful Improvements in Locks, of which the following is a specification, reference being had to the accompanying drawing, forming a part hereof.

10 This invention relates to locks of the type generally known as dead locks, in which the bolt is thrown from the inside of the door by a knob and is thrown from the outside of the door by a key. In such a lock the bolt is formed with the usual gate and gate posts on one side for coöperation with the cam or dog operated by the knob and on the other side with gate posts for coöperation with the cam or dog operated by the key. In the use 20 of such locks it is possible and it sometimes happens that the bolt is thrown only part way by the operation of the knob, from the inside of the door. When this happens it is generally impossible to throw the bolt in either direction by means of the key from the outside of the door. It is then necessary either to call the attention of some one within the house, to complete the movement of the bolt, or to secure the assistance of a 30 locksmith. The object of this invention is to improve the construction of the lock so that the bolt can be thrown by the key forward to its full extent and then thrown back or withdrawn, whereby the jamming of the lock, so that it cannot be operated by the key, becomes impossible. To accomplish this result the bolt is provided with a supplemental gate post which is placed on the same side of the bolt with the gate posts for co- 40 operation with the cam or dog operated by the key, but substantially opposite the main gate posts, with respect to the axis of rotation of the key and knob, and, while not interfering in any manner with the normal 45 operation of the lock, can be engaged by the key-operated cam or dog to throw the bolt completely forward from an intermediate position, when the same cam or dog can then engage one of the main gate posts to throw 50 the bolt back. The invention will be more fully explained hereinafter with reference to the accompanying drawing in which it is illustrated, and in which—

Figure 1 is a view of the lock in elevation, 55 with the cap plate removed, showing the bolt

partly thrown forward by the knob-operated cam or dog and jammed against movement by the coöperation of the key-operated cam or dog, which is shown by broken lines, with the usual gate posts.

60

Fig. 2 is a similar view showing the bolt thrown forward to the full extent, with the key-operated cam or dog, shown by broken lines, in position to withdraw the bolt.

Fig. 3 is a similar view showing the bolt 65 withdrawn by the key-operated cam or dog.

Fig. 4 is a view in section on the plane indicated by the line 4—4 of Fig. 1, looking in the direction of the arrows.

Fig. 5 is a view in elevation of the cap 70 plate.

Except as hereinafter indicated the lock may be of ordinary construction. As shown in the drawings, the casing *a* receives the bolt *b* and the tumbler *c* in the usual manner. 75 In the wall of the casing is mounted rotatably, in the usual manner, the knob-operated double cam or dog *d*, which coöperates, in the usual manner, with the gate *b'* and the gate posts *b*² formed on the corresponding 80 side of the bolt, the cam or dog also co-operating with the tumbler in the usual manner, as shown in Fig. 1, to disengage it from the stop *a'*, on the casing, with which it coöperates in the usual manner. A cap 85 plate *e*, adapted to be secured to the casing by a screw at *e'*, *e*², supports rotatably, in the usual manner, a key-operated bushing *f* and cam or dog *f'*, which is shown in full lines in Fig. 4 and by broken lines in the 90 other figures of the drawing. The key-operated cam or dog coöperates with the usual gate-posts *b*³ on the corresponding side of the bolt *b*, in the usual manner.

It is always possible and sometimes happens that, through inadvertence or accident, the bolt *b* is thrown only part way by the knob-operated cam or dog *d*, as shown in Fig. 1. If the key-operated cam or dog *f'* be then moved in an anti-clockwise 95 direction, it would strike upward against the lower edge of the right hand post *b*³ and would fail to move the bolt forward. Similarly, if the supplemental gate post, hereinafter referred to, were not provided 100 and the key-operated cam should be moved in a clockwise direction, it would strike upward against the lower edge of the left hand gate post *b*³ and would fail to throw the bolt back. The lock would then be 105 110

jammed and the bolt could not be thrown in either direction by the key-operated cam or dog f' .

To meet the difficulty just suggested and 5 to prevent the lock from becoming jammed so that the bolt cannot be thrown in either direction by the key-operated cam or dog, the bolt is provided, on the same side with the usual gate posts b^3 , but opposite the 10 posts b^3 (with respect to the axis of the knob and key bushing) with a supplemental gate post b^4 . Then, when the bolt has been left by the knob in the position shown in Fig. 1, the key-operated cam or dog f' can 15 be turned in a clockwise direction. It will first make contact with the supplemental gate post b^4 and will throw the bolt forward to the full extent, as represented in Fig. 2. The continued movement of the 20 key-operated cam or dog, in a clockwise direction, will then engage the tumbler c and disengage it from the stop a' and will then engage the right hand gate post b^3 and will throw the bolt back from this rearward position. The bolt can then be thrown 25 forward again either by the knob-operated cam or dog or by the key-operated cam or dog. It is impossible, therefore, that the lock be jammed in the manner described so 30 that the bolt cannot be operated by the key. It will be obvious that the invention can be

applied to locks of particular designs other than that shown in the drawing and that the invention, except as pointed out in the accompanying claims, is not limited in its 35 application to the particular lock shown and described herein.

I claim as my invention:

1. In a lock, the combination of a casing, a knob-operated cam or dog on one side of the casing, a key-operated cam or dog on the other side of the casing, and a bolt adapted for coöperation with the knob-operated cam and provided on one side with 40 posts for coöperation with the key-operated 45 cam and with a supplemental gate post for coöperation with the key-operated cam.

2. In a lock, the combination of a casing, a knob-operated cam or dog on one side of the casing, a key-operated cam or dog on the other side of the casing, and a bolt having gate posts on one side for coöperation with the knob-operated cam, gate posts on the other side for normal coöperation with the key-operated cam and with a supplemental gate post on the same side but opposite the usual gate posts, for coöperation with the key-operated cam in throwing the bolt forward from an intermediate position.

This specification signed this 23d day of 60 March, 1918.

HENRY H. CRANE.
